UNITED STATES PATENT OFFICE.

ALBERT C. DE SHEPPARD, OF BLOOMSBURG, PENNSYLVANIA.

HAT-PIN GUARD.

1,029,049.

Specification of Letters Patent. Patented June 11, 1912.

Application filed June 9, 1911. Serial No. 632,218.

To all whom it may concern:

Be it known that I, ALBERT C. DE SHEPPARD, a citizen of the United States, residing at Bloomsburg, in the county of Columbia and State of Pennsylvania, have invented a new and useful Hat-Pin Guard, of which the following is a specification.

This invention relates to hat pin guards.

The object of the invention is to provide a simple, thoroughly effective and easily applied and removed guard for hat pins, that will not only be positive in preventing the infliction of injury, but will also serve as an effective clamp or keeper to prevent loss 15 of the pin.

With the above and other objects in view, as will appear as the nature of the invention is better understood, the same consists, generally stated, in a hat pin guard comprising a sheath, a fixed guide therein, a clamping member co-acting with the guide, and a closure for the sheath constituting a means for directing a pin point between the guide and the clamping member. The 20 sheath is constructed from a cylinder of metal, permanently closed at one end and provided at its other end with an out-turned bead that is designed to be engaged by the closure around which the bead is flanged to 25 hold the two parts assembled. The closure is inwardly dished, and is provided at its apex with an orifice that aligns with the meeting point of the guide and the clamping member, the former of which is provided with a longitudinal groove, and with 30 inclined ends, one of which serves to direct the pin point into the groove, and the latter of which is resilient, and is preferably also provided with a channel to mate with that 35 of the guide to serve more effectively to assist in assembling the guard with the pin.

Further and more specific details of construction will be hereinafter fully described and claimed.

In the accompanying drawing forming a part of this specification, and in which like characters of reference indicate corresponding parts: Figure 1 is a view in side elevation displaying a hat pin equipped with the 45 guard of the present invention. Fig. 2 is a vertical longitudinal sectional view on an enlarged scale, through the guard. Fig. 3 is a transverse sectional view taken on the line 3—3 of Fig. 2. Fig. 4 is a perspective 50 detail view of the guide. Fig. 5 is a similar view of the clamping member or spring.

Referring to the drawing, 1 designates the sheath of the guard which is of tubular form and has one end 2 permanently closed, and the other end provided with an out-turned head 3. The sheath may be made of any suitable metal, and be plain, or ornamented in any manner to produce a neat and artistic appearance. Arranged within the sheath is a guide which is constructed 60 from a length of metal provided at each end with oppositely inclined terminals 4, soldered, riveted or otherwise secured to the sheath the body portion 5 of the guide as well as the ends, being provided with a longitudinal channel 6, the function of which is to facilitate the positioning of the guard on the pin, and to prevent the point of the latter from coming into contact with the inner surface of the sheath which would 65 tend to dull the former. The object for inclining the terminals or lugs 4 of the guard, and both at the same inclination, is to provide a means for facilitating the assemblage of the guard with the pin, and 70 also to render unnecessary the selection of the end that is to be inserted within the sheath in assembling the parts, as it will be immaterial which end is first entered.

Co-acting with the guide is a combined 75 guide and clamp 7, in the form of a two-leaved spring, one leaf or branch 8 of which bears against the inner wall of the sheath, and the other leaf 9 projects forwardly, and its terminal portion is designed to bear 80 against the guard, and is formed with an outturned end which will prevent the pin point from entering laterally between the arms of the clamp. In order to constitute the clamp member a guide, the leaf 9 is provided 85 adjacent to each terminal with a longitudinal channel 11 and 12 respectively, the former of which co-acts with the portion of the guide adjacent to the entrance mouth of the sheath, and the latter with the rear 90 end portion of the guide. The channels in the two parts are designed to mate, and are disposed opposite a central orifice 13 formed in a dished or cone-shaped closure 14 that is 95 designed to fit within the bead 3, and to be held therein by having the edges of the latter flanged over as shown at 15.

It is designed that the spring shall be of such tension, that it will clamp the pin against the guide with sufficient force to 100 preclude the possibility of accidental separation, so that loss will be prevented. The 105

outer end of the sheath will be rounded, so that should it strike the face of a bystander, no possible injury would result.

To apply, it will only be necessary to bring the pin point opposite the orifice 13, which will be easily accomplished by reason of the dished shape of the closure, and then push the guard over the pin point, the latter entering between the opposite faces of the clamping member and of the guide to force the former to one side. To remove the guard, it will only be necessary to hold the pin with one hand and pull the guard from off the pin with the other.

In addition to the clamping member engaging the pin, the inner or rear end of the leaf 9 is raised or bowed in rear of the guide to lie in the path of the pin so that upon the pin being inserted, the pointed end is deflected upward by the inner end of the clamping member to bind the pointed end of the pin at the inner end of the sheath between the inner ends of the guide and the clamping member.

The improvements herein described, while simple in character, will be found thoroughly effective for the purposes designed,

and will co-act in the presentation of a simple, durable and highly practical form of guard.

I claim:

1. A hat pin guard comprising a sheath, a longitudinal fixed guide therein, and a clamping member having a forwardly projecting leaf co-acting with the guide, to receive the pin, the rear end of the said leaf being bowed to extend into the path of the pin in rear of the guide and adapted to deflect the pointed end of the pin and bind the end of the pin between the said bowed portion and the rear end of the guide.

2. A hat pin guard embodying a sheath, a fixed guide therein, yielding means co-acting with the guide to receive a hat pin, and means in rear of the guide and within the sheath for deflecting the pointed end of the pin.

In testimony that I claim the foregoing as my own, I have hereto affixed my signature in the presence of two witnesses.

ALBERT C. DE SHEPPARD.
